UNITED STATES PATENT OFFICE

2,604,916

MOUNTING OF THE DRUM IN HOUSEHOLD GRATERS

Jean Mantelet, Bagnolet, France, assignor, by
mesne assignments, to Le Moulin-Legumes
Corporation, Wilmington, Del., a corporation of
Delaware

Application November 24, 1947, Serial No. 787,834
In France October 10, 1947

6 Claims. (Cl. 146—177)

1

The present invention has for its object to provide improvements in the mounting of the rotary drum of portable household graters of the type comprising a magazine secured to a handle and intended to contain the substance to be grated, a drum forming a grater secured to a crank enabling a rotary movement to be imparted to it about its axis, and a pusher pivotally connected to the handle and adapted to penetrate into the magazine so as to urge the substance to be ground, contained in the magazine, against the drum.

In all the prior household graters thus constructed, the drum is journalled at each of its ends either in a cylindrical bearing surface extending all around its periphery, or in two symmetrical parts of bearing surfaces which may be arranged laterally or at the top and bottom parts of the drum, it being possible, in particular in this latter case, for one of said bearing surfaces to be formed by the lower edge of the magazine.

The grater according to the invention is distinguished by the mounting of the rotary drum and is characterised by the following main points which may exist separately or in combination:

a. The drum is suspended from the magazine by attaching means having on either side of the drum at least three bearing points, two of which are located outside and the third inside the drum or vice-versa, the third bearing point being arranged symmetrically with respect to the two first ones, whereas blocking means are provided to prevent any movement of the drum in axial direction.

b. The attaching means and/or the blocking means are removable so as to enable the drum to be removed and placed in position.

c. The guide means and/or the abutment means are urged when in the operative position, by resilient means.

d. The attaching means and the stationary blocking means are mounted on the grater body.

e. The attaching means and/or the blocking means comprise rotary members which are rotated by contact with the drum.

f. The same members simultaneously perform the function of attaching means and blocking means.

g. The grater body is provided on one side, at its lower edge, with an annular flange, the cross-section of which is of the shape of an inwardly facing groove and which is adapted to accommodate one of the circular edges of the drum provided with a flange at right angles thereto while the opposite lower edge of the magazine is provided with a right angle flange adapted to engage the inner face of an annular flange,

2

U-shaped cross-section, having an inwardly facing groove provided at the other circular edge of the drum and directed towards its medial portion, a blocking means being adapted to be placed on either side of the drum so as to prevent any axial movement of said drum.

The invention furthermore includes other features which will become apparent from the ensuing description and from the accompanying drawing, in which:

Fig. 1 is a perspective view of a preferred embodiment of the present invention; and

Fig. 2 is a vertical central longitudinal section, on a larger scale, of the embodiment shown in Fig. 1.

In the modification shown in Figs. 1 and 2, the grater body and hopper 2 is provided on one side, at the lower part thereof, with a semi-circular attaching means 17 of U-shaped cross-section 20 adapted to receive one circular edge of the drum 7 provided with a vertical flange 18. The upper part of the flange 17 is provided with an elongated opening 19 into which can penetrate a swinging bolt 20 which is pivoted at 21 on the grater body 2.

The other side of the grater body 2 has at the lower part thereof a circular recess adapted to accommodate the drum 7; the edge of said recess is bent over at right angles so as to form a flange 30 23 adapted to co-operate with the upper part of a circular flange 22 of U-shaped cross-section formed on the circular edge of the drum 7 opposite the end provided with the right angle flange 18.

35 The movement of the drum 7 in the vertical direction is limited by the U-shaped flange 17 co-operating with the flange 18, on the one hand, and by the flange 23 co-operating with the U-shaped flange 22. The axial movement of the drum is limited by the vertical flange 18 confined between the vertical portion of the U-shaped flange 17 and the bolt 20.

To remove the drum, it is only necessary to swing the bolt 20 about its pivot 21 so as to withdraw it from the opening 19, thereby enabling the drum to be removed by an axial movement towards the left of Fig. 2.

I claim:

50 1. In a household grater in combination, a grater body; a tubular grater drum having an inner and an outer drum face and having two opposite circular edges; an annular flange arranged along one of said opposite circular edges of said tubular grater drum forming along said edge an annular inwardly facing groove positioned outside said tubular grater drum; first attaching means arranged on said grater body

along the other of said opposite circular edges of said tubular grater drum, and including arcuate groove-shaped supporting means engaging said tubular grater drum along said other circular edge thereof so as to support said grater drum along said edge; second attaching means arranged on said grater body along the first mentioned of said opposite edges of said tubular grater drum engaging the inner surface of said annular inwardly facing groove formed by said annular flange arranged along said first mentioned opposite edge of said tubular grater drum; and blocking means on said grater body preventing sliding of said tubular grater drum in axial direction.

2. In a household grater in combination, a grater body; a tubular grater drum having an inner and an outer drum face and having two opposite circular edges; first attaching means arranged on said grater body along the other of said opposite circular edges of said tubular grater drum, and including arcuate groove-shaped supporting means engaging said tubular grater drum along said other circular edge thereof so as to support said grater drum along said edge; second attaching means arranged on said grater body along the first mentioned of said opposite edges of said tubular grater drum and engaging the inner surface of said annular inwardly facing groove formed by said annular flange arranged along said first mentioned opposite edge of said tubular grater drum; and blocking means combined with at least one of said attaching means for preventing sliding of said tubular grater drum in axial direction.

3. In a household grater in combination, a grater body; a tubular grater drum having an inner and an outer drum face and having two opposite circular edges; an annular flange arranged along one of said opposite circular edges of said tubular grater drum forming along said edge an annular inwardly facing groove positioned outside said tubular grater drum; first attaching means arranged on said grater body along the other of said opposite circular edges of said tubular grater drum, and including arcuate groove-shaped supporting means engaging said tubular grater drum along said other circular edge thereof so as to support said grater drum along said edge; second attaching means arranged on said grater body along the first mentioned of said opposite edges of said tubular grater drum engaging the inner surface of said annular inwardly facing groove formed by said annular flange arranged along said first mentioned opposite edge of said tubular grater drum; blocking means combined with at least one of said attaching means for preventing sliding of said tubular grater drum in axial direction; and a turning member directly secured to said tubular grater drum.

4. In a household grater in combination a grater body; a tubular grater drum having an inner and an outer drum face and having two opposite circular edges; an annular flange arranged along one of said opposite circular edges of said tubular grater drum forming along said edge an annular inwardly facing groove positioned outside said tubular grater drum; first attaching means arranged on said grater body along the other of said opposite circular edges of said tubular grater drum directly attaching the same to said grater body in such a manner as to enable rotation of said tubular grater drum about its axis, but to prevent its turning about

said first attaching means; second attaching means arranged on said grater body along the first mentioned of said opposite edges of said tubular grater drum engaging the inner surface of said annular inwardly facing groove formed by said annular flange arranged along said first mentioned opposite edge of said tubular grater drum; and blocking means on said grater body preventing sliding of said tubular grater drum in axial direction.

5. In a household grater in combination a grater body; a tubular grater drum having an inner and an outer drum face and having two opposite circular edges; an annular flange arranged along one of said opposite circular edges of said tubular grater drum forming along said edge an annular inwardly facing groove positioned outside said tubular grater drum; first attaching means arranged on said grater body along the other of said opposite circular edges of said tubular grater drum directly attaching the same to said grater body in such a manner as to enable rotation of said tubular grater drum about its axis; second attaching means arranged on said grater body along the first mentioned of said opposite edges of said tubular grater drum engaging the inner surface of said annular inwardly facing groove formed by said annular flange arranged along said first mentioned opposite edge of said tubular grater drum; first blocking means on said grater body preventing turning of said tubular grater drum about said attaching means; and second blocking means on said grater body preventing sliding of said tubular grater drum in direction of its axis.

6. In a household grater in combination a grater body; a tubular grater drum having an inner and an outer drum face and having two opposite circular edges; an annular flange arranged along one of said opposite circular edges of said tubular grater drum forming along said edge an annular inwardly facing groove positioned outside said tubular grater drum; first attaching means arranged on said grater body along the other of said opposite circular edges of said tubular grater drum directly attaching the same to said grater body in such a manner as to enable rotation of said tubular grater drum about its axis; second attaching means arranged on said grater body along the first mentioned of said opposite edges of said tubular grater drum engaging the inner surface of said annular inwardly facing groove formed by said annular flange arranged along said first mentioned opposite edge of said tubular grater drum; first blocking means on said grater body preventing turning of said tubular grater drum about said attaching means; second blocking means on said grater body preventing sliding of said tubular grater drum in direction of its axis; and a turning member directly secured to said tubular grater drum.
